RECLOSED CIRCUIT INTERRUPTER

Application filed July 10, 1931. Serial No. 549,829.

My invention relates to the art of electric distribution.

The principal object of my invention is to provide a novel form of thermal relay 5 which may be applied to circuit interrupters of the overload type or used for other purposes. The relay is especially adaptable to circuit interrupters of the "reclosing" type.

Such reclosing interrupters are now in 10 general use and ordinarily consist of a circuit interrupter of the overload type which is not only provided with means for opening the interrupter upon the occurrence of an overload, but is also provided with means 15 for automatically reclosing the interrupter within a short but usually definite period after it has opened so that if the conditions producing the overload have ceased, the circuit will be automatically restored to normal 20 operation. If the overload persists upon reclosing the interrupter, the interrupter immediately reopens. Such reclosing interrupters are often arranged to close a plurality 25 of times but it is necessary for their successful operation that the number of reclosures be limited since it sometimes happens due to line failure or other causes that the condition causing the overload persists and does not disappear when the circuit is opened.

30 Many overloads caused by swinging wires or other transient conditions do not recur upon reclosing the interrupter either the first or some subsequent time, in which event no permanent discontinuance of electric service results 35 since the interrupter remains closed after the transient condition disappears. It is found in practice that the number of reclosures need not be very great, six reclosures being commonly required, since if the condition causing the overload does not disappear prior to the sixth reclosure, it is usually a 40 condition of sufficient permanence to require the attention of the lineman and one that makes further attempts to operate the line extremely dangerous and usually futile. My invention is well adapted to provide exactly 45 the sort of service required in a reclosing interrupter.

Previous inventors have constructed interrupters that would provide for reclosures

preferably a number of times in which if the circuit remains normal for a short but predetermined period after any reclosure, the controlling means for the interrupter resets (or returns to its initial position) and is then 55 in a position to again reclose the interrupter the predetermined number of times, just as if the interrupter had not previously opened. One of the principal purposes of using reclosing interrupters is to keep the lines in 60 service where a swinging wire or other transient condition occurs. It sometimes happens, however, that this condition recurs at intervals of one hour or more over long periods, during which periods the interrupter 65 opens frequently but never remains open. This may result in a defective line being kept in service when it should be repaired. This defect in the operation of the ordinary reclosing interrupter is due to the fact that 70 it entirely resets (or resumes its initial condition) after the interrupter has remained closed for a few minutes after it has opened once or more in response to unfavorable transient conditions and that once entirely 75 reset, it then functions without regard to any condition which has preceded the resetting.

It is an object of my invention to provide 80 a reclosing interrupter which for a long period after any successful reclosing, if reopened by a recurrence of the unfavorable transient condition, will then be influenced in its further operation by conditions occurring prior to the successful reclosing. For example, a standard type of reclosing interrupter may be set to reclose six times and then remain open if the unfavorable condition of the circuit persists. If it remains 85 closed upon any of said six reclosures for a period of say two minutes, it resets; that is, it adjusts itself so that it will again reclose six times. As a result, if an unfavorable condition, such as a swinging wire, exists on the circuit which recurs at intervals of three minutes, the interrupter will open and close every three minutes indefinitely. By my invention it is possible to provide a reclosing interrupter which if it opens upon the occurrence of an unfavorable condition as often 90 95 100

as six times in a week, it will then stay open. Such long time periods are not usually necessary however, and if the reclosing mechanism has means allowing it to reclose not 5 more than once an hour, it meets operating conditions.

In my invention the effects of several openings are cumulative. For example, if the interrupter is so constructed as to open six 10 times upon a persistent unfavorable condition and it stays closed after having opened five times, it will reopen and stay open after an interval of several minutes if the condition again persists long enough to open the 15 interrupter twice, and will be operative over even a longer interval if the condition persists long enough to open the interrupter three or more times.

All this I accomplish by using a thermal 20 relay which stores heat during the time the interrupter is open, the amount of heat so stored depending upon the number of times the interrupter opens, this heat being dissipated slowly after the interrupter finally 25 remains closed so that additional openings of the interrupter, even after a considerable time interval, add heat to the supply of heat remaining from the original storage so that the interrupter will stay open after a smaller 30 number of reclosures than it would if a longer time had elapsed since its prior reclosure.

Further objects and advantages will be made evident hereinafter.

In the drawings, which illustrate one form 35 of thermal relay and one application of that relay:

Fig. 1 is a front elevation of the relay;

Fig. 2 is a section through the thermal storage portion thereof;

Fig. 3 is a side elevation;

Fig. 4 is a diagram of connections of the relay applied to a conventional circuit interrupter.

The thermal relay shown in Figs. 1, 2, and 45 3 includes a thermal storage element 10. The element 10 consists of a coil of wire 11 wound on thin mica 12 over a metal tube 13 (having a closed lower end), the wire 11 having terminals 14. The wire 11 is covered 50 with heat insulation 15. Inside the tube 13 is a body of low melting alloy 16. Alloys having melting points below 200° F. are available (and quite suitable) for this purpose. Projecting into the tube 13 and normally embedded and rigidly locked in the 55 body of alloy 16 (when the alloy is cold) is a plunger 17. The plunger 17 is rigidly locked to a cross-bar 18 which is secured to the upper ends of two slide rods 19. The 60 slide rods 19 pass loosely through holes in two supports 20 which support the tube 13 and which are themselves supported on a slate or other insulating panel 21.

Carried on the lower end of the slide rods 65 19 is a cross-bar 22 of hard rubber or other

insulating material. Carried on the cross-bar 22 and movable therewith are two fingers 23 preferably formed of spring brass (or bronze), each of these fingers being connected to a post 24 fixed on the panel 21 through a flexible copper cable 25 so that the cross-bar 22 can move up and down over a limited path without disconnecting the fingers 23 from the posts 24.

The plunger 17 and the above described parts are shown in Fig. 1 in their upper or normal locked position, the plunger 17 being held in this position by the alloy 16 as long as the alloy remains solid, and falling by the weight of the plunger and its associated parts as soon as the alloy melts.

Supported between two heads 30 on the panel 21 below the parts above described is a thermal relay reset coil 31 inside which a magnetic core 32 is free to slide vertically, this core being pulled upwardly by the coil 31 whenever an electric current of sufficient strength is passed through the coil.

Projecting through the upper head 30 is a stem 33 which is rigidly secured to and moves with the core 32. Carried on but insulated from the stem 33 is a reset disc 34 which is so placed and spaced that it makes contact with both the fingers 23 when the fingers drop due to the melting of the alloy 16 or when it is moved upwardly due to the movement of the core 32. The end of the stem projects above the disc 34 a sufficient distance to strike the cross-bar 22 after good electrical contact is made between the fingers 23 and the disc 34.

Insulated from and carried by the core 32 is a main thermal relay disc 35 which in its lower position makes electrical contact with bronze fingers 36 carried on posts 37 set in the panel 21. When the coil 31 is energized and the core 32 is pulled up thereby, this contact is broken due to the disc 35 being lifted from the fingers 36.

The thermal relay above described is intended to break the circuit through the fingers 36 whenever a definite quantity of electricity measured in watt seconds, for example, has flowed through the wire 11. This is accomplished by connecting one terminal 40 of the coil 31 through a post 24 and a flexible cable 25 to a finger 23, the other terminal 41 of the coil being connected to one terminal of a battery 42 which is connected through a wire 43 to the other post 24 and through the other flexible cable 25 to the other finger 23. When so connected the thermal relay operates as follows.

The parts being in the position shown in the drawings, current is passed through the wire 11. This wire is preferably, but not necessarily, a wire such as those used in heating appliances which have a small increase in resistance as they increase in temperature and which are highly resistant to oxidation or corrosion. Due to the electrical resistance

of this wire, heat is developed therein which flows through the mica 12 and the tube 13 to the alloy 16, which is therefore gradually heated during the time current passes through the wire 11. It is to be noted that the quantity of heat so delivered to and stored in the alloy 16 is proportional to the wattage of the current flowing in the wire 11. As heat is stored in the alloy 16, the temperature of the alloy is increased gradually to the melting point. The time required to reach this temperature is called the "time element" of the relay. By suitably proportioning the amount of alloy 16 and the resistance of the wire 11, almost any desired time element may be obtained.

As soon as the alloy is melted sufficiently to allow the plunger 17 to fall freely, the plunger and parts connected thereto fall and the fingers 23 make contact with the disc 34, completing the circuit from the battery 42 through the coil 31.

The energization of the coil 31 pulls the core 32 upwardly which causes the end of the stem 33 to push upwardly on the bar 22 and push the plunger 17 back into its initial position, the fingers 23 maintaining their contact with the disc 34 so that the coil 31 remains energized throughout this movement and after it is completed. As the core 32 moves upwardly, it lifts the disc 35. If desired, this upward movement of the disc 35 can be used to open the circuit through the wire 11 by connecting one of the terminals 14 through a wire 44 with one of the fingers 36, the other finger 36 and the other terminal 14 being connected to the circuit feeding the wire.

After the core 32 has moved up and the plunger 17 is restored to its upper position, current will therefore be cut off from the wire 11 and no more heat will be delivered to the alloy 16, which will start to cool. The rate of cooling is determined by the characteristics of the heat insulation 15. If a very slow rate of cooling is desired, the entire thermal storage element can be enclosed in a vacuum bottle. Such an extremely slow cooling rate is not necessary, however, for most uses to which the relay is put and ordinary asbestos paper wound around the wire 11 is sufficient to supply the necessary heat insulation 15. Whatever the rate of cooling, the alloy will eventually cool and solidify, again locking the plunger in the position shown in the drawings. If now the circuit through the coil 31 is opened, the core 32 drops and the relay parts are all in the initial position shown in the drawing, in which position the disc 35 rests on the fingers 36 and the wire 11 may be again energized.

The above-described relay therefore opens the circuit between the fingers 36 whenever a definite amount or watt seconds of energy in the form of heat has been delivered to the alloy 16, or when a definite amount of energy

in the form of electricity has flowed through a circuit which includes the wire 11. If the current flowing in the wire 11 has a constant value or a constant average value, in the case of an alternating or pulsating current, the circuit will be broken at the fingers 36 a certain definite time after the current starts to flow.

The principal value of the relay resides in its integrating characteristics. If the current flowing in the wire 11 is intermittent or irregular in value, the wire 11 automatically integrates the energy values of this current so that the relay is responsive to the average energy flowing through the wire 11 during any period.

It should be noted that the relay is also fully operative if for any reason the plunger 17 is locked in its lower position at the beginning of the operative cycle, since in this position the core 32 is held in its lower position against the pull of the coil 31 and the circuit between the fingers 36 cannot be broken until the alloy 16 melts and allows the plunger 17 to rise. The relay thus does not open the circuit until exactly the same time has elapsed as would have elapsed had the plunger 17 been in its upper position at the start of the cycle.

An application of the thermal relay just described is illustrated in the diagram of connections shown in Fig. 4. In this diagram 101 is a standard three-pole circuit interrupter adapted to open a circuit 102 of a three-phase alternating circuit. The mechanism is shown in the conventional diagrammatic manner as consisting of a toggle 103 which is closed to close the circuit interrupter by a closing coil 104.

In the diagram I have shown a circuit interrupter which is closed by a solenoid. Many circuit interrupters are closed by motor operated mechanisms and my invention is equally applicable to motor operated circuit interrupters, the closing coil shown and other electrically energized means for actuating the contacts being generally included in the term "electrically energized actuators". Moreover, many circuit interrupters to which my invention is applicable are hydraulically, pneumatically, or mechanically energized by various forms of force applying devices generally included in the broader term "actuators".

The interrupter is opened by a trip coil 105 acting on the toggle 103. If the closing coil 104 is energized, the interrupter is closed and if the trip coil 105 is energized, the interrupter is opened.

A pilot switch 106 is provided having a movable contact 107 which moves with the main contacts of the interrupter, closing a circuit between contacts 108 in its upper position and between contacts 109 in its lower position.

The above parts 101 to 109 inclusive constitute an electrically operated circuit interrupter which is standard in the art and therefore shown diagrammatically. Other well known forms of circuit interrupters may be substituted therefor without departing from the spirit of my invention.

The circuit interrupter may be caused to open upon the occurrence of any abnormal circuit condition in the circuit 102 by any well known means such as an overload relay 110 having a coil 111 connected to the secondary 112 of a series transformer 113 whose primary 114 is connected into the distribution circuit 102. The relay 110 is provided with two contacts 115 which are electrically connected to each other by a movable bridging member 116 whenever the current in the circuit 102 exceeds a predetermined value. Other types of relay or tripping devices may be used without departing from the spirit of my invention.

It is desirable that the interrupter should not close immediately upon being opened, a short time interval being preferably provided before reclosure to allow the circuit 102 a short "dead" interval so that any free arcs or insulator flash-overs which may have caused the previous overload or short circuit may have a chance to clear themselves. An interval of thirty seconds is generally considered long enough for this purpose although this should not be regarded as a definite and invariable practice, much longer times being perfectly practical. Some types of circuit interrupters, notably spring actuated devices in which the spring is compressed by a small motor, require a sufficiently long interval for their operation, but the usual solenoid operated interrupter will reclose very quickly. If it is desired to delay the reclosing of the interrupter for a longer period than is inherent to the interrupter mechanism, a time limit relay is used.

My thermal relay is well adapted for use as a time limit relay and can be so used but for simplicity in the diagram (Fig. 4) I have shown a time limit relay 120 having an actuating coil 121 which acts upon a core 122 to pull it upwardly when the coil 121 is energized. The core 122 carries a bridging member 123 which makes electrical contact between contacts 124 just before it reaches its upper position. A dash-pot 125 retards the upward movement of the core 122 to produce the desired time interval. The dash-pot is preferably so constructed that it is effective only on the upward stroke of the core 122, allowing the core to fall freely whenever current is cut off from the coil 121. In actual practice I prefer to substitute for the solenoid type of relay, which is conventional in the art, one of the later forms of induction relays which performs the same function, and which closes an electric circuit at

the end of a definite time interval after the relay is itself energized. The solenoid relay lends itself better to diagrammatic representation and is therefore shown.

In addition to the automatic reclosing mechanism, it is, of course, necessary to provide means by which an operator can manually control the opening and closing of the interrupter. For this purpose I provide a manual control switch 130 having a movable arm 131 pivoted at 132 and normally held by springs in contact with a central contact 133, but which is so arranged that it can be moved (and held) by hand to make contact with a contact 134 if it is desired to close the interrupter, or to make contact with a contact 135 if it is desired to open the interrupter, the arm 131 snapping back into its central position whenever the hand is removed. If desired, locking means may be provided for locking the manual control switch in either the opening or closing position.

Some source of electrical energy must be provided for actuating the various apparatus above described and I have shown a battery 140 as a convenient source, without, of course, intending to limit myself to a battery, since various other sources may be used, or, if the apparatus is suitably designed, it can be energized from the source of energy feeding the circuit 102.

In the diagram (Fig. 4) the parts are shown in the position they assume in normal position; that is, with the circuit interrupter closed and a normal load on the circuit 102. If now an overload occurs, the movable member 116 of the overload relay is lifted and electrical connection is made thereby between the contacts 115. This closes a trip circuit through the trip coil through wires 200, 201, 202, 203, 204, 205, and 206 and the battery 140. Note that the contacts 108 of the pilot switch 106 are bridged by the member 107 and are in this circuit.

This energization of the trip coil causes the circuit to open the pilot switch 106, then opening the trip circuit, thus cutting off current from the trip coil 105.

The opening of the circuit causes the member 107 of the pilot switch 106 to bridge the contacts 109, and the coil 121 of the time element relay is energized through a time element circuit consisting of wires 210, 211, 212, and 213, through fingers 36 and thermal relay disc 35, wires 221, and 215, through the movable arm 131 of the manual control switch 130, through the wires 216 and 200, through the battery 140 to the wires 206 and 205, and back to the pilot switch 106. This starts the time element relay 120, which we will assume is set to operate in thirty seconds.

At the time the interrupter opens, it starts the operation of the time element relay 120,

the wire 11 in the thermal relay being energized from the pilot switch 106 through a thermal relay circuit consisting of the wires 210, 211, 220, 11, 214, 213, 221, 215, the arm 131, 5 the wires 216 and 200, the battery 140, and wires 206 and 205 back to a contact 109 of the pilot switch. The wire 11 then transmits energy to the alloy in the thermal switch as long as the thermal relay circuit is closed. 10 Let us assume that the thermal relay is so constructed that the thermal relay circuit must be closed for a little less than three minutes to melt the alloy. Note that the fingers 36 are in the thermal relay circuit. The thermal 15 relay will therefore not operate prior to the time the time limit relay (which is set to operate in thirty seconds) operates.

The time limit relay operates at the end of thirty seconds, closing a closing coil circuit passing through 124, this circuit consisting of the wires 230, 231 and 210, the lower contacts 109 of the pilot switch, the wires 205 and 206, the battery 140, the wires 200 and 216, the arm 131, the wires 215, 221, 213, 25 and 232, back to a contact 124. This energizes the closing coil 104 which closes the interrupter. As the interrupter closes, the member 107 opens the circuit between the contacts 109 of the pilot switch 106, and 30 opens the time element relay, the thermal relay, and the closing circuit. The member 123 of the time element relay therefore drops to its initial position as shown in Fig. 4 and current is cut off from the wire 11 of the 35 thermal relay, which starts to cool slowly.

If during the thirty seconds the interrupter has been open the condition that caused the overload on the circuit 102 to occur has disappeared, the interrupter will stay closed and 40 the alloy in the thermal relay will gradually cool until all conditions are again normal. This condition will generally disappear if it was due to an insulator flashover, a swinging wire, or some other transient condition, in 45 which event the circuit 102 suffers merely a thirty second interruption and then functions normally.

If, however, for any reason the condition causing the overload has not disappeared 50 prior to the reclosing of the interrupter, as soon as the interrupter recloses the overload relay 110 again operates (as soon as the interrupter recloses) due to the overload and energizes the trip coil 105, causing the interrupter to open. The time limit relay 120 is then energized and after it has had time to operate, that is to say, in thirty seconds, the interrupter recloses. If the overload still persists, it again opens. This alternate opening and reclosing (after an interval of thirty seconds) would continue indefinitely were it not for the thermal relay which is set to limit the number of such reclosures. We can assume, for example, that it is set to allow 60 six reclosures and prevent a seventh.

The thermal relay prevents this seventh reclosure as follows. The interrupter having been reclosed the sixth time and having opened due to the persistence of the overload, 70 the time limit relay 120 is energized but before it can close the circuit at the contacts 124 and thus cause a reclosure, the alloy 16 of the thermal relay melts or softens sufficiently to allow the plunger 17 to drop. This closes a circuit through the fingers 23, a wire 250, the coil 31, a wire 251, the wire 215, the arm 131, the wire 216, the wire 200, the battery 140, the wire 206, and a wire 252. The coil 31 being energized, lifts the member 35 from the fingers 36. 80

In the form of my invention shown the coil 31 and certain associated parts act as a "reset means". That is, as soon as the alloy 16 melts and cross bar 22 (with its connected parts) falls, the coil 31 is energized (through the fingers 23) and the moving element associated with the coil "resets" the cross bar 22. That is, the cross bar 22 is pushed up to its original position. Current is simultaneously cut off the wire 11 (at the fingers 36) and the alloy 16 also cools or resets. 90

The opening of the circuit at the fingers 36 opens the circuit through the wire 221 of the wire 11 of the thermal relay, and the circuit through the wire 213 to the time element relay 120. The time limit relay 120 therefore does not complete its operation but drops back to its initial position so that the closing coil 104 cannot be energized and the interrupter stays open. The coil 31 of the thermal relay is, however, still energized and holds the plunger 17 in its upper position where it is locked by the alloy 16 as the alloy cools. The parts will remain in this position until an operator discovers that the circuit is open. 95

The operator can then throw the manual control switch into the closing position so that the arm 131 contacts with the contact 134 and the closing coil 104 is energized through a wire 260, thus closing the interrupter. If the line has been repaired, the overload will not recur and the interrupter stays closed. The operator then lets go of the manual switch, which snaps back to its central position in contact with the contact 133. With the breaker closed, it can be manually tripped by throwing the arm 131 into contact with the contact 135, which energizes the trip coil through a wire 262 and the wire 203. If the arm 131 were allowed to return to its central position when released, the interrupter would automatically reclose and therefore it is desirable to provide means for locking the arm 131 in contact with the contact 135. In most central stations some visible means is now provided for attachment to the manual switch locking it in the opening position to indicate that the interrupter has been deliberately opened and should not 110 115 125 130

be closed unless the operator is sure that there are no workmen on the line fed by the interrupter. This visible means will obviously prevent automatic reclosure since it holds the 5 manual switch open. If such separate visible means is not used, it is preferable to so construct the manual switch 130 that it will not snap back to its central position from the opening position when released by the operator.

It will be noted that in the form of my invention illustrated the reclosing of the circuit interrupter is finally terminated by opening a switch in the circuit of the closing coil. 15 As will be readily understood by one skilled in the art, this termination can be accomplished by closing a switch which shunts the closing coil or by a latch or toggle which locks the mechanism of the interrupter. All 20 such expedients, which I consider in view of the state of the art as mechanically equivalent to the switch used by me, are included in the general term "inhibitor" which should be understood to mean anything which inhibits 25 its or prevents movement of something else.

It will be noted that by the use of the thermal relay I provide a device which integrates abnormal conditions over a considerable time. By providing heat insulation 30 about the wire 11, the rate of cooling of the alloy 16 may be made very slow. If, therefore, the interrupter opens under overload one or more times and then stays closed for a considerable time, if the overload then 35 recurs and the interrupter opens, the alloy may retain sufficient heat to cut down the number of subsequent reclosures. The amount of heat so retained is (roughly) inversely proportional to the time that the interrupter has remained closed.

Suppose, for example, the interrupter has reclosed five times successively under an overload which then disappears. If the interrupter remains closed for say twenty-four 45 hours, the alloy, if a certain amount of heat insulation is provided, will have entirely cooled so that the interrupter will reclose six times before locking open. If, however, the interrupter opens thirty minutes after 50 it has been closed subsequent to five successive reclosures, the alloy will be sufficiently hot to allow say three reclosures, and if it opens in fifteen minutes, it will allow only two reclosures. This is important since it is not desirable to allow repeated reclosures on a damaged line.

While I have shown a reclosing interrupter using a specific heat storage device in which I depend upon the melting of a body of metal 60 to allow one member of the device to move from one position to another, it will be obvious to one skilled in the art that reclosing interrupters could be made using various other forms of heat storage devices such as 65 those which depend merely upon expansion

under the influence of heat, many well known forms of heat storage devices of the expansion type being available for this purpose.

I claim as my invention:

1. In an electrically energized device, the combination of: an electrically energized element; a switch for controlling the flow of electrical energy through said element; a heat storage device having a member which moves from a primary position to a secondary position whenever said heat storage device has received a definite amount of heat; an electrically driven reset; means by which said reset operates said switch; means by which said movement of the member in said heat storage device from said primary position to said secondary position actuates said reset; and means by which said reset when actuated by said means returns said member to its primary position. 70

2. In combination with an electric circuit system: a switch in said system having separable contacts through which the electric current of said system passes; opening means for causing said contacts to open upon the occurrence of a predetermined condition in said system; closing means for causing said contacts to close; an inhibitor adapted to prevent said closing means from operating; a heat storage device having a moving element, said heat storage device being so designed that said moving element moves from an inactive position to an active position whenever a definite quantity of heat has been delivered to said heat storage device; means for delivering heat to said heat storage device while said contacts are open; means by which said moving element when in its active position actuates said inhibitor to prevent said closing means from operating; a reset means actuated whenever said moving element reaches its active position; means by which the actuation of said reset means resets said element in its inactive position; and means for discontinuing the supply of heat to said heat storage means whenever said reset means operates. 90

3. In combination with an electric circuit system: a switch in said system having separable contacts through which the electric current of said system passes; opening means for causing said contacts to open upon the occurrence of a predetermined condition in said system; closing means for causing said contacts to close; an inhibitor adapted to prevent said closing means from operating; a heat storage device having a moving element, said heat storage device being so designed that said moving element moves from an inactive position to an active position whenever a definite quantity of heat has been delivered to said heat storage device; means for delivering heat to said heat storage device while said contacts are open; means by which said moving element when in its active position 100 110 115 120 125 130

actuates said inhibitor to prevent said closing means from operating; a reset means actuated whenever said moving element reaches its active position; means by which 5 the actuation of said reset means resets said element in its inactive position; means for locking said reset means in its operated position; means by which an attendant operating the system can release said reset means from 10 its locked position; and means for discontinuing the supply of heat to said heat storage means whenever said reset means operates. means by which said reset means prevents further heat from entering said heat storage means after said reset means is thrown into active position by said heat storage means; and a three-way switch so connected that in 70 its normal position it enables said heat storage means to receive heat as above described, in its off position it disconnects said heat storage means and actuates the opening means, and in its closed position it disconnects said heat storage means and actuates the closing means. 75

4. In an electric circuit system having a switch with separable contacts through which the electric current of said system passes, said switch having opening and closing means, a control system comprising: a heat storage means adapted to receive heat when said separable contacts are separated and to prevent the reclosure of the switch after the heat storage means has received a definite increment of heat; a reset means actuated from said heat storage means after it has received a definite increment of heat; means by which said reset means prevents further heat from entering said heat storage means after said reset means is thrown into active position by said heat storage means; and means by which an attendant of the system may cause said reset means to assume its inactive position.

15 7. In an electric circuit system having a switch with separable contacts through which the electric current of said system passes, said switch having opening and closing means, a control system comprising; a heat storage means adapted to receive heat when said separable contacts are separated and to prevent the reclosure of the switch after the heat storage means has received a definite increment of heat; a reset means actuated from said heat storage means after it has received a definite increment of heat; means by which said reset means prevents further heat from entering said heat storage means after said reset means is thrown into active position by said heat storage means; means by which said reset means in passing from its inactive to its active position forces said heat storage means into its inactive po- 80 85 90 95

35 5. In an electric circuit system having a switch with separable contacts through which the electric current of said system passes, said switch having opening and closing means, a control system comprising: a heat storage means adapted to receive heat when said separable contacts are separated and to prevent the reclosure of the switch after the heat storage means has received a definite increment of heat; a reset means actuated from said heat storage means after it has received a definite increment of heat; means by which said reset means prevents further heat from entering said heat storage means after said reset means is thrown into active position by said heat storage means; means by which said reset means in passing from its inactive to its active position forces said heat storage means into its inactive position; and means by which an attendant of the system may cause said reset means to assume its inactive position.

40 100 6. In an electric circuit system having a switch with separable contacts through which the electric current of said system passes, said switch having opening and closing means, a control system comprising: a heat storage means adapted to receive heat when said separable contacts are separated and to prevent the reclosure of the switch after the heat storage means has received a definite increment of heat; a reset means actuated from said heat storage means after it has received a definite increment of heat; means by which said reset means prevents further heat from entering said heat storage means after said reset means is thrown into active position by said heat storage means; means by which said reset means in passing from its inactive to its active position forces said heat storage means into its inactive position; and means by which an attendant of the system may cause said reset means to assume its inactive position; and a three-way switch so connected that in its normal position it enables said heat storage means to receive heat as above described, in its off position it disconnects said heat storage means and actuates the opening means, and in its closed position it disconnects said heat storage means and actuates the closing means.

45 105 7. In an electric circuit system having a switch with separable contacts through which the electric current of said system passes, said switch having opening and closing means, a control system comprising: a heat storage means adapted to receive heat when said separable contacts are separated and to prevent the reclosure of the switch after the heat storage means has received a definite increment of heat; a reset means actuated from said heat storage means after it has received a definite increment of heat; means by which said reset means prevents further heat from entering said heat storage means after said reset means is thrown into active position by said heat storage means; means by which said reset means in passing from its inactive to its active position forces said heat storage means into its inactive position; and means by which an attendant of the system may cause said reset means to assume its inactive position.

50 110 8. In an electric circuit system having a switch with separable contacts through which the electric current of said system passes, said switch having opening and closing means, a control system comprising: a heat storage means adapted to receive heat when said separable contacts are separated and to prevent the reclosure of the switch after the heat storage means has received a definite increment of heat; a reset means actuated from said heat storage means after it has received a definite increment of heat; means by which said reset means prevents further heat from entering said heat storage means after said reset means is thrown into active position by said heat storage means; means by which said reset means in passing from its inactive to its active position forces said heat storage means into its inactive position; and means by which an attendant of the system may cause said reset means to assume its inactive position.

55 6. In an electric circuit system having a switch with separable contacts through which the electric current of said system passes, said switch having opening and closing means, a control system comprising: a heat storage means adapted to receive heat when said separable contacts are separated and to prevent the reclosure of the switch after the heat storage means has received a definite increment of heat; a reset means actuated from said heat storage means after it has received a definite increment of heat; further heat heat storing means after said reset means is thrown into active position by said heat storage means; and a three-way switch so connected that in its normal position it enables said heat storage means to receive heat as above described, in its off position it disconnects said heat storage means and actuates the opening means, and in its closed position it disconnects said heat storage means and actuates the closing means, said reset means being released from the reset position whenever said

three-way switch is moved from its normal position.

9. In an electric circuit system having a switch with separable contacts through which the electric current of said system passes, said switch having opening and closing means, a control system comprising: a heat storage means adapted to receive heat when said separable contacts are separated and to prevent the reclosure of the switch after the heat storage means has received a definite increment of heat; a reset means actuated from said heat storage means after it has received a definite increment of heat; means by which said reset means prevents further heat from entering said heat storage means after said reset means is thrown into active position by said heat storage means; means by which said reset means in passing from its inactive to its active position forces said heat storage means into its inactive position; and a three-way switch so connected that in its normal position it enables said heat storage means to receive heat as above described, in its off position it disconnects said heat storage means and actuates the opening means, and in its closed position it disconnects said heat storage means and actuates the closing means, said reset means being released from the reset position whenever said three-way switch is moved from its normal position.

10. In combination with an electric circuit system; a switch in said system having separable contacts through which the electric current of said system passes; opening means for causing said contacts to open upon the occurrence of a predetermined condition in said system; closing means for causing said contacts to close; an inhibitor adapted to prevent said closing means from operating; a heat storage device having a moving element, said heat storage device being so designed that said moving element moves from an inactive position to an active position whenever a definite quantity of heat has been delivered to said heat storage device; means for delivering heat to said heat storage device while said contacts are open; a time limit relay adapted to actuate the closing means in a definite time after said separable contacts have opened, unless prevented by the inhibitor; means by which said moving element when in its active position actuates said inhibitor to prevent said closing means from operating; a reset means actuated whenever said moving element reaches its active position; means by which the actuation of said reset means resets said element in its inactive position; and means for discontinuing the supply of heat to said heat storage means whenever said reset means operates.

11. In combination with an electric circuit system: a switch in said system having separable contacts through which the electric

current of said system passes; opening means for causing said contacts to open upon the occurrence of a predetermined condition in said system; closing means for causing said contacts to close; an inhibitor adapted to prevent said closing means from operating; a heat storage device having a moving element, said heat storage device being so designed that said moving element moves from an inactive position to an active position whenever a definite quantity of heat has been delivered to said heat storage device; means for delivering heat to said heat storage device while said contacts are open; a time limit relay adapted to actuate the closing means in a definite time after said separable contacts have opened, unless prevented by the inhibitor; means by which said moving element when in its active position actuates said inhibitor to prevent said closing means from operating; a reset means actuated whenever said moving element reaches its active position; means by which the actuation of said reset means resets said element in its inactive position; and means for discontinuing the supply of heat to said heat storage means whenever said reset means operates.

In testimony whereof, I have hereunto set my hand at Los Angeles, California, this 6 day of July, 1931.

FORD W. HARRIS.
